UNITED STATES PATENT OFFICE.

WILLIAM H. WORTHEN, OF BROOKLYN, NEW YORK, ASSIGNOR TO GUILD & GARRISON, OF SAME PLACE.

PISTON FOR COMPRESSOR AND OTHER PUMPS AND ENGINES.

SPECIFICATION forming part of Letters Patent No. 311,629, dated February 3, 1885.

Application filed March 31, 1884. (No model.)

To all whom it may concern:

Be it known that I, WILLIAM H. WORTHEN, of the city of Brooklyn, in the county of Kings and State of New York, have invented a new and useful Improvement in Pistons for Compressors and other Pumps and Engines, of which the following is a specification.

My invention is applicable generally to pumps and engines, but is particularly intended for the pistons of air and gas compressors.

In dry compressors it is necessary that there should be as little clearance as possible at each end of the stroke, and that the back end as well as the front end of the piston should be as nearly as possible a plane surface without projections or depressions. Any projection from the back end of the piston necessitates a corresponding depression or cavity in the cylinder-head, and depressions or cavities in the head as well as those in the piston form air-spaces, which impair the efficiency of the pump or compressor by reason of the expansion of the compressed air or gas with which they are fitted at each change of piston-stroke.

In carrying out my invention I employ a piston composed, principally, of a body and a follower, between which are held the packing-rings, and which is secured by screws to the body, and the piston-rod is formed with a taper fitting a taper socket in the piston-body, and is secured in the piston-body by a nut which is preferably cylindric externally, and received in a cylindric countersink or recess in the piston-body.

This invention consists in novel combinations of parts, which are particularly herein-after described, and pointed out in the claims.

In the accompanying drawings, Figure 1 is an axial section of a piston embodying my invention, and Fig. 2 is a plan view thereof.

Similar letters of reference designate corresponding parts in both figures.

A designates the piston-body, having at the front end the flange a, and B designates the follower, also having a flange, a'.

C are packing-rings of any well-known or suitable construction, which are held between the flanges a a' of the piston-body and follower A B.

At the back end of the piston-body A is a

hub or projection, b, within which is formed a circular countersink, c, and the follower B has a circular central aperture snugly fitting the exterior of said hub or projection b in a well-known manner.

D designates the piston rod, having a taper portion, D', which fits a taper socket, d, in the piston-body A and forms a slight shoulder, e. The taper portion D' of the rod extends nearly but not quite to the bottom of the countersink c, and beyond that point the rod has a screw-thread, f, on which is fitted a circular nut, E, which is snugly received in the countersink c. In said nut E are holes g, with which a wrench having projecting studs or spurs may be engaged.

In the face of the follower B is formed a large countersink, h, which is of such depth that the end of the hub or projection b and the outer face of the nut E will be approximately flush with the bottom of the countersink, and within the circle or circumference of this countersink are arranged the screws i, whereby the follower B is secured to the piston-body A. The heads i' of these screws are fitted in minor countersinks j in the bottom of the main countersink h, and the heads are flush with the bottom of said main countersink h.

F designates the guard-plate, which is of a thickness corresponding to the depth of the main countersink h, and is snugly fitted therein, the inner face of the guard-plate being in close proximity to or bearing against the screw-heads i' and the outer face of the nut E. The guard-plate F is provided with a central aperture, k, which receives the end of the piston-rod D through it, and is secured in place by a pin or key, l, passing through the rod D just outside the guard-plate.

The aperture k in the guard-plate F may be large enough to slip over the threaded end f of the piston-rod; but preferably said aperture is screw-threaded, and the guard-plate is screwed upon the rod, thus securing it in place in addition to the pin l.

It will be seen from the foregoing description that the screws i and nut E cannot move outward relatively to the guard-plate F, because of their close proximity to the inner face thereof, and as the turning of said screws and nut in loosening would necessarily result in

such outward movement it will be clear that they are securely locked against unscrewing.

What I claim as my invention, and desire to secure by Letters Patent, is—

5. 1. The combination, with a piston-body, A, and a follower, B, having countersinks *j* in its outer face, of screws *i*, inserted through the follower and into the body, and having their heads *i'* fitting the countersinks *j* in said follower, and a guard-plate secured at the back of the piston and covering the heads of said screws, substantially as and for the purpose herein described.

2. The combination, with a piston-body, A, and a follower, B, having in its outer face a main countersink, *h*, and minor countersinks *j* in the bottom of said main countersink, of screws *i*, inserted through the follower and into said body, and having their heads *i'* fitting the minor countersinks *j*, and a guard-plate, F, secured in said countersink *h*, and covering said screws, substantially as and for the purpose herein described.

3. The combination, with the piston-body having the countersink *c*, and a rod, D, having a screw-threaded end, *f*, of a nut, E, upon said rod, fitting the countersink *c* in said body, a follower, B, having the countersinks *j*, screws *i*, inserted through the follower and into the body, and having their heads *i'* fitting said countersinks *j*, and a guard-plate secured at the back of the piston and covering said nut and screws, substantially as and for the purpose herein described.

4. The combination, with the body A, having the hub or projection *b* and countersink *c*, of the rod D D' *f*, the nut E, the follower B, having the main and minor countersinks *h*, *j*, the screws *i* *i'*, and the guard-plate F, all substantially as and for the purpose herein described.

WM. H. WORTHEN.
